REINFORCING CONCRETE PATCH

Louis S. Wertz, Shaker Heights, Ohio

Application June 15, 1936, Serial No. 85,236

12 Claims. (Cl. 72—71)

This invention relates to the restoration of concrete structures and has particular reference to the reinforcing of a concrete patch. In concrete construction, whether in new work or in the restoring of old structures, it is desirable to provide reinforcement within the structure to withstand tensile stresses. This is usually done by an arrangement of steel rods or wires embedded in the structure. In order that these reinforcing members be efficient they should take up any tension to which the concrete in which they are embedded may be subjected. Where a concrete patch has been applied to a concrete structure, tensile stresses, such as induced by temperature changes, are apt to cause cracks or fissures in the patch and particularly in the bond between the new and old concrete. It is, therefore, an object of this invention to provide a method of reinforcing concrete used in the restoration of structures so that the new concrete will be relieved of substantially all tensile stresses and to avoid as far as possible, the formation of such cracks.

Another object of this invention is to provide a method of reinforcing concrete used in the restoration of structures which will minimize voids or spaces between the new concrete and the old structure.

Another object is to provide an improved anchor to be used in reinforcing replacement concrete and which may be used independently and which will take the tensile stresses between the new and old concrete.

A further object of the invention is to provide a method of reinforcing replacement concrete so that in addition to the bond afforded between the two concretes, it will be adequately anchored to the old structure.

A still further object is to provide a method of reinforcing replacement concrete which is rapid and simple, yet inexpensive, and readily adaptable to various types of repair work.

In the accompanying drawing in which I have illustrated a use of my method;

Fig. 1 is a diagrammatic plan view of a reinforced concrete patch with a portion of the cavity not completely filled;

Fig. 2 is a section on the line 2—2 of Fig. 1;

Fig. 3 is a detail in section showing the manner in which the anchors are secured in the structure;

Fig. 4 is a perspective of a portion of an anchor showing the manner of connecting the reinforcing network thereto; and

Fig. 5 is a perspective of an improved reinforcing anchor.

Referring to the drawing by numerals of reference, it will be seen that the invention comprises a tensioned network 10 which may be formed of any suitable material having adequate tensile properties, such as steel, preferably in the form of wire.

In restoring concrete structures it is preferable to first chip away the loose scale and disintegrated portions of the structure, so that the surface 11 of the old structure adjoining the cavity 10 to be filled will be firm and hard. In order that the marginal portions of the patch will not be tapered to a thin or feather edge, it is desirable to remove sufficient of the old structure so that around the marginal portion or contour of the 15 region to be patched there is room for a substantial depth of new concrete. When one or more portions of the cavity to be filled with new concrete are of considerable depth such as indicated at 25, it is preferable to employ anchoring devices 27 of improved design, shown in perspective in Fig. 5. They comprise a body portion formed with an upset end 28 provided with an expansion collar 29, and an expanding wedge 30. The opposite end of the body portion is formed 20 into a loop 31. Crossarms 33 and 34 have a central portion positioned in and have their ends 25 extending radially from the aperture of the loop 31. In some cases it may be desirable to weld the crossarms 33 and 34 in the loop 31. These anchors or reinforcing trees, having an elongated 30 body portion, are placed in the deep cavity portion 25 at suitably spaced intervals, such for example as a distance between centers of four times the height of the individual reinforcing 35 anchors. With the secondary reinforcing anchors in position, new concrete is applied to the old concrete in the deep portions 25 of the cavity so that the secondary anchors are substantially 40 embedded therein and serve to hold the new concrete in position while it is setting, as well as serving to reinforce the structure after the new concrete has hardened.

The reinforcing network 10 is then tensioned between tension anchor bolts 20 placed around 45 the periphery of the cavity to be filled with elements of the network 10 extending directly between the anchor bolts 20. It is located substantially close to the surface 23 of the replacement concrete. In such a position it will tend to retain the entire patch of replacement concrete 50 within the cavity and provide a strong coherent surface.

The tension anchor bolts 20, have a hook 15 at one end of the shank 16, and the opposite end 55

17 is provided with any suitable means to hold it within a recess formed in the concrete, such as the upset end 17, which prevents its being pulled out of the expansion head 18, when the latter is expanded by means of the wedge portion 19. The anchor bolts 20 preferably have their axes at an angle less than a right angle to the direction of the stress in the reinforcing network.

If the patch to be repaired is of considerable area, but not deep enough to use the reinforcing trees described above, a number of intermediate anchor bolts 24 are secured in the old concrete at suitable spaced intervals. These intermediate anchor bolts engage the network 10, preferably at an intersection of individual wires 22, and thereby serve to prevent deflection of the reinforcing network 10 and tie in the entire mass of replacement concrete 13 to the old concrete 12. The reinforcing network 10 comprises a number of individual rods or wires 22 which may be suitably secured together at their intersections such as by spot welding to prevent relative movement and to more effectively reinforce the new concrete. This network is formed to approximate the shape of the cavity to be filled. The tensioning of the network is preferably accomplished by means of tie-wires 26 which are looped about the wire retaining hook 15 of the tension anchors 20 and about an individual wire 22 of an adjacent portion of the reinforcing network 10. When the network is thus suspended in the cavity the tie-wires 26 may be twisted by means of a suitable implement such as a nail inserted in the loop of the tie-wire, or otherwise tensioned to hold the network tightly in place. The reinforcing network 10 may be tied in or otherwise secured to the anchoring devices or reinforcing trees by suitable short lengths of wire 35 to firmly bind the new masonry or concrete 13 to the old masonry or concrete 12. When the crossarms 33 and 34 are not welded in the apertures of the loop 31 they may be held in place in any other suitable manner as by passing the wire 35 around the vertical angles formed by their intersection. The reinforcing trees, while affording a strong connection between the old masonry 12 and new masonry 13, do not interfere with the filling of the cavity 25 and afforded ample space for the cement to enter all the interstices of the old concrete.

After the reinforcing network 10 has been tensioned between the anchoring devices, the remainder of the cavity is filled with concrete so that the reinforcing network and anchors are embedded therein. However, if the patch or area to be reconstructed is of such a nature that the concrete may be readily applied through the reinforcing latticework and around the reinforcing and anchoring trees, the filling of the cavity with concrete may be done in one operation after all the reinforcing elements have been placed in position, instead of applying it in two operations as mentioned above. Also, in patches of the type where there are relatively few or no deep portions, so that relatively few, if any, reinforcing trees are used, and the tensioned network 10 is employed to furnish substantially the entire reinforcement for the concrete, the concrete may be applied in one operation.

The present invention provides a method for reinforcing replacement concrete to be used in repairing masonry which distributes tensile stresses such as may be induced by temperature changes across substantially the entire patch, which tensile stresses may be taken up by the re-

inforcing network and the old masonry structure. Also, the installation of the reinforcing wire network with an original tensile stress enables it to function from the time of its installation, and it is unnecessary for the concrete to be first subjected to excessive stresses before the reinforcing network will function. Furthermore, reinforcing trees have been provided which are complete units individually and serve to firmly bond the new masonry to the old.

The method which has been shown and described is capable of numerous modifications in order to carry out the invention in connection with the reinforcing of concrete or other masonry in various types of replacement work.

Although I have shown and described but a single application of my invention in reinforcing a concrete patch, it is to be understood that many modifications are within the scope of the invention and intended to be included in the following claims.

What I claim is:

1. The method of reconstructing concrete, comprising the steps of preparing the old concrete, affixing thereto a plurality of anchoring means for retaining a reinforcing network, tensioning a reinforcing network between the anchoring means so that the network will be positioned adjacent the surface of the reconstructed concrete, and applying the new concrete.

2. The method of installing reinforcing steel in a concrete structure to be patched, which comprises removing the disintegrated portion of the old structure, removing portions of the old structure for a substantial depth around the marginal portion of the region to be patched, affixing to the old concrete a plurality of anchoring means within said marginal portion for retaining a reinforcing network, securing a reinforcing network to the anchoring means below and adjacent to the normal surface of the concrete structure, and tensioning the reinforcing network throughout the region to be patched.

3. The method of reconstructing concrete comprising, removing the disintegrated portions of the old structure within the area to be reconstructed, affixing a plurality of independent concrete anchoring means within the deeper portions of said area, tensioning on additional anchoring means within said area a reinforcing network over the area adjacent but below the normal surface of the concrete being reconstructed and applying the new concrete.

4. The method of reconstructing concrete comprising the steps of removing the disintegrated portions of the old structure within the area to be reconstructed, affixing a plurality of independent concrete anchoring means within the deeper portions of said area, applying new concrete to the deeper portions, tensioning a reinforcing network over the area below the normal surface of the concrete being reconstructed, and applying the remainder of the new concrete.

5. The method of reconstructing concrete comprising the steps of removing the disintegrated portions of the old structure within the area to be reconstructed, affixing a plurality of independent concrete anchoring means within the deeper portions of said area, applying new concrete to the deeper portions, tensioning a reinforcing network over the area below the normal surface of the concrete being reconstructed, connecting the independent anchoring means and the network and applying the remainder of the new concrete.

6. The method of reconstructing concrete comprising the steps of removing disintegrated portions of the old structure, affixing a plurality of independent concrete supporting anchors within the area to be reconstructed, and tensioning anchors adjacent the marginal portions of said area, applying the portion of the new concrete to the deeper portions, stretching and tensioning a reinforcing network between the tensioning anchors and applying the remainder of the new concrete.
7. A reinforced concrete patch which comprises tensioning and anchoring means affixed to the old structure adjacent the periphery of the area to be reconstructed, a reinforcing network stretched between the anchoring means, said network positioned substantially close to the surface of the replacement masonry, and elements of the network extending directly between the anchoring means whereby said elements are tensioned to transmit stresses directly to the old structure, said anchoring means having their axes at an angle less than a right angle to the direction of the stress induced by the reinforcing network, and secondary anchoring means securing the reinforcing network at spaced intervals to the old structure, said secondary anchoring means positioned in the deeper portions of the cavity being repaired.
8. The method of reconstructing old concrete structures having deep and shallow portions to be filled in, comprising the steps of removing disintegrated portions of the old structure, affixing a plurality of concrete holding means in the solid portions of the old structure to reinforce the new concrete to be applied in the deeper portions, securing tensioning anchors around the marginal portion of the area to be reconstructed, applying a portion of the new concrete to said deeper portions, positioning and tensioning a reinforcing network between said tensioning anchors, and securing the network to said concrete holding means, and applying the remainder of the new concrete.
9. A reinforced concrete patch, comprising a plurality of anchoring means having portions thereof embedded in the old concrete a substantial distance beneath the surface thereof, said anchoring means being disposed in the old concrete adjacent the marginal portions of the patch, and having portions for securing a reinforcing network thereto disposed near the surface of the replacement concrete, a reinforcing network tensioned between the anchoring means and positioned near the surface of the replacement concrete, said network having elements extending directly between said anchoring means, and concrete embedding the reinforcing network.
10. A reinforced concrete patch, comprising a plurality of anchoring means having portions thereof embedded in the old concrete a substantial distance beneath the surface thereof, said anchoring means being disposed in the old concrete adjacent the marginal portions of the patch, and having portions for securing a reinforcing network thereto disposed near the surface of the replacement concrete, a reinforcing network tensioned between the anchoring means and positioned near the surface of the replacement concrete, said network having elements extending directly between said anchoring means, concrete embedding the reinforcing network, and secondary anchoring means, substantially longer than the first mentioned anchoring means, disposed in the deep portions of the patch and provided with crossheads to reinforce and hold the replacement concrete in the deeper portions of the patch.
11. A reinforced concrete patch, comprising a plurality of anchoring means having portions thereof embedded in the old concrete a substantial distance beneath the surface thereof, said anchoring means being disposed in the old concrete adjacent the marginal portions of the patch, and having portions for securing a reinforcing network thereto disposed near the surface of the replacement concrete, a reinforcing network tensioned between the anchoring means and positioned near the surface of the replacement concrete, said network having elements extending directly between said anchoring means, concrete embedding the reinforcing network, and secondary anchoring means, substantially longer than the first mentioned anchoring means, disposed in the deep portions of the patch and provided with crossheads to reinforce and hold the replacement concrete in the deeper portions of the patch, and means to secure said tensioned reinforcing network to said secondary anchoring means to assist in holding the network against displacement.
12. A reconstructed concrete area having marginal portions and deeper portions, comprising substantially rigid reinforcing means in the deeper portions of the area, anchored to the old concrete, a reinforcing network disposed below, but adjacent the normal surface of the concrete being reconstructed, secured to and tensioned between a plurality of anchoring means embedded in the old concrete around the marginal portions of said area, said network having elements thereof extending directly between the last mentioned anchoring means, and concrete embedding all of said reinforcements.

LOUIS S. WERTZ.
